APPARATUS FOR ROLLING PIPE

William Bark, John Henry Schmidt, and James V. Mazurie, Gary, Ind., assignors to National Tube Company, a corporation of New Jersey

Application June 2, 1932, Serial No. 615,018

1 Claim. (Cl. 80—11)

This invention relates to the manufacture of pipe and particularly to an improvement in the present methods of operating pipe rolling mills and to certain details of their construction.

5 These mills, which are also called plug mills, are now made and operated so that the pipe is returned by pinch-rolls after its rolling pass, the mandrel or plug being removed and the rolling rolls separated to permit this. It is then necessary to turn the pipe and repass and again return it before a round shape is obtained as the rolls do not so shape the pipe with a single pass because of their tendency to thicken its wall at their pass line. Thus it is necessary to move the 10 pipe between the rolls four times.

One of the objects in the present instance is to operate a rolling mill so that a greater output of pipe results, and another is to construct a rolling mill to include features which contribute 15 to the effectiveness of this operation.

Having reference to the accompanying drawing which illustrates one specific form of the invention:

Figure 1 is a cross-sectional side elevation.

25 Figure 2 is a cross-section of the roll stand showing a pass.

Figure 3 is an enlarged detail from Figure 1.

Figure 4 is a detail.

These various figures show a rolling mill comprising a stand of rolls mounted in a housing 2 and oppositely extending alined pipe troughs 3. A pipe pusher 4 is arranged at the remote ends of each trough for forcing pipes into the bite of the rolls, rolling pressure being maintained by 30 screws 5 driven by a motor 6.

A mandrel bar 7 is arranged over the right-hand trough and is carried by a thrust block 8 which is reciprocable by means of a crank and arm 9. This crank is driven by a motor 10 through 180 degree arcs and may be stopped at dead center to more easily take thrusting forces.

45 A pin 12 is fixed to the mandrel or plug end of the bar 7, the drawing showing the two integral, although the pin might as well be screwed or otherwise fastened to the bar. This pin has a straight surface 13 of sufficient length to carry a mandrel and a reduced portion or peripheral groove 14 immediately therebeyond, the remainder of the pin being a continuation of the first surface.

50 A mandrel or plug 15 is slipped over the pin 12 and has conical depressions 16 surrounding both ends of its pin receiving hole. It is held on the pin by an expansible ring 17 which has a conical end fitting in one of the depressions in

the end of the plug, the latter having room for a slight lateral play which permits this assembly. Preferably, the end of the mandrel bar is conical so as to fit the depression in that end of the plug, otherwise should the plug have only one end made with the conical depression mentioned it will acquire a front and rear which may be easily confused by a plug handler in his haste. The ring itself consists of two interpivoted semi-circles of metal which swing outwardly.

5 One important feature of the above mandrel or plug is its double working surface. Ordinarily, this is shaped to work the tube when passing over it in only one direction, but here it is shaped on both sides of its center to operate as a working surface, and so far as this feature is concerned, it makes a truly double-ended plug.

10 A water bosh 18 is located on the left of the stand of rolls and a vertically reciprocable mandrel carriage 19 is arranged therein. This carriage is operated by a cylinder motor 20 and when raised is in line to receive the mandrel when the latter's carrying bar is reciprocated forwardly by a half turn of the crank 9. A rest support 21 normally supports and steadies the extreme 15 end of the pin 12, but this may be thrown out of the way by a cylinder motor 22 to permit removal of the plug and passage of the tube. Naturally, the locking ring 17 must be removed during the plug's removal.

20 The new rolling method consists essentially in giving a tube forward and reverse passes through rolls whose rolling pressures are maintained during the second or reverse pass. Thus both passes are effective in shaping the tube instead of but one and production is doubled. That is, instead of separating the rolls and using pinch-rolls or other means to return the tube with a useless motion, the right-hand pusher 4 is operated to shove each singly passed pipe back 25 into the rolls, which are of course now reversed, so that the next movement both returns the pipe and gives it its needed second pass. The pipe is turned, generally manually, before this 30 second pass in the usual manner. The structural details previously described are not here mentioned because their contributing factors to 35 this method are so obvious.

40 Although a specific form of this invention has been shown and described in accordance with the patent statutes, it is not intended to limit the scope exactly thereto, except as defined by the following claim.

45 We claim:

5

10

15

20

25

30

35

40

45

50

55

A tube rolling mill including the combination of a stand of longitudinal tube rolling rolls, oppositely extending aligned tube troughs for said stand, tube pushers arranged at the ends of said troughs remote from said stand so as to push tubes into the latter, a mandrel bar over one of said troughs and having a mandrel-carrying pin on its end adjacent said stand, a reciprocable block for mounting the end of said bar remote from said stand, a crank axially aligned with and spaced from said block, an arm interconnecting said crank and block, a motor for revolving said arm, a double-ended mandrel releasably carried on said pin, the latter being sufficiently long to extend beyond said mandrel, a quickly removable support for the portion of said pin extend-

ing beyond said mandrel, a water bosh on the side of said stand opposite said bar, said block being reciprocable between positions where it positions said bar with said mandrel between the rolls of said stand and where it positions said bar with said mandrel over said bosh, a mandrel carriage and a quick-acting reciprocating motor mounting said carriage for vertical reciprocation from a position where it engages said mandrel when said block is reciprocated to its second named position to one where it immerses said 10 mandrel in water in said bosh. 5
